UNITED STATES PATENT OFFICE

EDWARD F. HERSCHEDE, OF CINCINNATI, OHIO

WRIST-WATCH BAND

Application filed April 30, 1926. Serial No. 105,829.

This invention relates to wrist straps and fastening means therefor and has for an object the provision of a simple and adjustable securing means.

Another object is to provide a structure of the class referred to which is inexpensive of manufacture and assembly.

Another object is to provide a structure of this kind which is adaptable to use with wrist straps of solid metal, tortoise shell or other substances of suitable characteristics.

These and other objects are attained by the means described herein and disclosed in the accompanying drawings, in which:

Fig. 1, is a perspective view of a wrist watch and strap having a device of my invention embodied therein.

Fig. 2, is a cross sectional view on line 2—2 of Fig. 1.

Fig. 3, is a similar view showing a modified form of the device of my invention.

Fig. 4, is a cross sectional view showing another modified form of the device.

A wrist watch case 8 carries at its opposite sides pins 9 for mounting the wrist strap or bracelet members 10 and 11. The strap portions 10 and 11 may be made of flat strips of suitable material finished uniformly or in contrast with the case 8. Tubular portions 12 on the ends of members 10 extend between the lugs 13 on the case and receive the pins 9.

The free end 14 of member 11 has a perforation 15 and a communicating reduced aperture therethrough forming an opening 35 for receiving a headed stud adjustably retained on the strap member 10. The member 10 as shown in Figs. 1, 2 and 3, has a plurality of spaced perforations 17 therethrough aligned with aperture 16 in member 11. The 40 perforations 17 are omitted in the modification shown in Fig. 4.

A flat C-shaped clamp 18 of resilient or bendable material has a body portion 19 which rides against the outer face 20 of member 10 and has curved lugs 21 extending about the opposite edges 22 of said strap member. The lugs 21 abut the inner face of the strap 10, and in the structure shown in Fig. 4 frictionally bind the clamp 19 thereto. This form is preferably made of metal. A stud 23 extends

through and is secured in the clamp 19 with shouldered portion 24 abutting the outer face of the clamp. Shoulder 24 is of a diameter such as to be slidably received in aperture 16.

A head 25 on stud 23 is adapted to be passed 55 through a perforation 15 and rides over the top face of strap member 11 as shoulder 24 enters aperture 16. In this way the strap members are secured together when placed about the wrist of a wearer.

In the forms shown in Figs. 1, 2, and 3, the stud 23 has an end lug 26 projecting through the clamp 18 and seating in a selected one of perforations 17 to preclude movement of the clamp relatively to member 10. In these 65 embodiments the clamp may be comparatively flexible so that the end lug may be withdrawn by pulling the clamp slightly away from the strap, the flexibility of the clamp permitting the limited movement required. 70

In the embodiment shown in Fig. 4, the frictional engagement of the clamp on the strap is such as to permit adjustment but to preclude slippage.

The parts being of comparatively thin material provide a light weight and comfortable strap which is adapted to be easily adjusted to fit the wrist. The strap members may be curved and the normal resiliency of the material permits them to conform to the wrist 80 when the clamp is in any of its adjusted positions. The securing means is positive and easy to open and close.

From the foregoing the operation of the device is apparent. The strap ends are overlapped to permit entry of head 25 through aperture 15, whereupon the shoulder 24 enters aperture 16.

The straps and clamp may be of like or dissimilar material, it being essential only that the materials be flexible or bendable but rigid enough to retain the desired shape.

What I claim is:

1. In a device of the class described the combination of a pair of strap members 95 adapted to overlap one another at their free ends, one of said members having a series of longitudinally spaced perforations therein, the other member having a single opening adjacent its end and aligned with the perfora- 100

tions in the first mentioned member, a clamp member on the first mentioned member and having curved lugs extending about opposite side edges of said member, a stud extending through the clamp and having one end seating in a selected one of the perforations in the strap member, and a spaced head on the other end of the stud for entry into the single opening in the second mentioned strap member.

10 2. In a device of the class described the combination of a wrist strap member having longitudinally spaced perforations therein, a bendable clamp member comprising a body disposed transversely across one face of the strap and slideable longitudinally thereof and resilient lugs extending about opposite edges of the strap and engaging the opposite face thereof, a lug on the clamp for entry in the 15 perforations in the strap for precluding slideable movement of the clamp, a second strap for overlapping the first mentioned strap and cooperating means on said strap and clamp for locking the strap members against longitudinal separation.

20 3. In a wrist watch strap construction the combination of a strap having perforations therein, a C-shaped clamp member slidably carried by said strap and a stud fixed in the 25 clamp member and having ends extending in opposite directions therefrom, one of said ends serving to enter a perforation in the strap to fix the clamp against longitudinal movement thereon, the other of said ends 30 serving to detachably connect a second strap to the clamp.

In testimony whereof, I have hereunto subscribed my name this 26th day of April, 1926.

EDWARD F. HERSCHEDE.
